FREDERICK H. OBERSCHMIDT, OF CLEVELAND, OHIO, ASSIGNOR TO THE CUTLER-HAMER MFG. CO., OF MILWAUKEE, WISCONSIN, A CORPORATION OF WISCONSIN.

ELECTRICAL CONTROLLER.

Application filed March 22, 1924. Serial No. 700,985.

This invention relates to electrical controllers and more particularly to timing devices therefor.

An object of the invention is that of providing for more ready and accurate timing of certain control functions.

Another object is that of providing against variation of the time element of the controller with variations in electrical condition of the controlled circuit.

Another object is that of providing a controller as aforecharacterized comprising few and simple parts which may be substantially of standard construction.

Other objects and advantages will herein after appear.

In the accompanying drawing, wherein are illustrated by way of example certain of the embodiments which the invention may assume in practice,

Figure 1 is a diagrammatic view illustrating a proposed construction; while,

Figs. 2 and 3 are similar views illustrating modified constructions.

Referring to the drawing, and first to Fig. 1 thereof, the same illustrates by way of example an adaptation of the present principles to produce automatically and definitely timed stopping of an A. C. motor M, the latter to be supplied from lines L¹ L² subject to control by an electroresponsive switch 5 in conjunction with the means to be hereinafter described.

Said switch, which may comprise standard or conventional parts, is provided with a magnetic frame 6 having a pivoted, contact carrying armature 7, the contact 8 of which is adapted in the closed or attracted position of said armature to engage fixed main and auxiliary contacts 9 and 10. Said switch is further provided with an energizing coil 11 to be connected across the supply lines in shunt to the motor, subject to control by a starting push button or equivalent switch 12, a suitable current limiting resistance 13 being included in circuit with said coil. Obviously closure of contactor 8 serves to bridge the fixed contacts 9 and 10 thereby shunting

push button 12 and maintaining energization of coil 11 after opening of switch 12 in a well known manner.

An additional coil 14 is provided on frame 6 in a relation to derive energy inductively from coil 11 during energization of the latter. A heating coil or equivalent device 15 is arranged in circuit with the coil 14 to be heated by current flowing in their joint circuit. A suitable thermo-responsive contacting device 16 subjected to influence of heater 15 is arranged to control continuity of a circuit shunting the coil 11.

Upon closure of switch 12 the energizing circuit of coil 11 is completed whereupon switch 5 responds and completes the motor circuit. Also as a result of energization of coil 11 induced current flows in the circuit of coil 14 and heater 15. The thermo-responsive contactor 16 being subjected to the resultant rise in temperature is adapted, subject to a definite time element, to close the circuit shunting the coil 11 whereupon switch 5 drops out and deenergizes the motor M and opening the maintaining circuit of coil 11. Also as a result of deenergization of coil 11, coil 14 and heater 15 are also deenergized whereupon element 16 is adapted to resume its normal relation interrupting the shunt around coil 11 thereby resetting the elements of the controller for subsequent starting of motor M in the manner aforescribed.

The construction shown in Fig. 2 is in general quite similar to that described. However, in this instance the coil 14 of switch 5^a is omitted or consolidated with coil 11 to produce the structure depicted at 11^a, thereby obviating the necessity of providing separate coils upon the switch frame. The thermostatic element 16^a is moreover shown in the form of a thermostatic resistance grid adapted upon passage of current therethrough to become heated and consequently deformed to close circuit as aforescribed. Also the push button 12^a is of the latched-in type thus obviating the necessity of providing a maintaining contact on switch 5^a.

In practice the switch 12^a may be prefer-

ably spring biased to open position as shown, a pivoted latch 17 spring biased to latching position and having also a suitable releasing knob or handle being provided for holding in said switch when closed. Said latch 17 is provided with a contact portion or element arranged in the energizing circuit of coil 11^a as shown, whereby upon engagement of said contact portion by the element 16^a the 10 coil 11^a is shunted and switch 5^a permitted to open. However, under these conditions the element 16^a, or the major portion thereof is maintained in circuit and hence continues to undergo deformation for ultimate tripping 15 of latch 17 whereupon switch 12^a is adapted to open, deenergizing element 16^a to permit cooling of the latter and thus affect resetting of the controller to provide for restarting of the motor upon depression of switch 12^a. 20 The latch 17 may be of conductive material adapted when in latching relation to contact with the bridging element of switch 12^a. However, it is preferred to insulate said members as shown to thereby insure that circuit 25 interruption occur at the switch contacts rather than between the switch contactor and the latch. A suitable stop or abutment, such as indicated at 19, is preferably provided to limit the movement of latch 17 under the action of its biasing means.

A variable resistance device 18 may be arranged to be in circuit with the element 16^a for varying the time element of the latter. Also plural taps may be provided upon the 35 coil 11^a, as indicated, for an analogous purpose, whereas an adjustable screw is preferably provided upon the latch 17 for affording further calibration.

The construction illustrated in Fig. 3 differs from that of Fig. 2 in that the element 16^a is arranged permanently in shunt to coil 11 whereby the energy applied to the former is maintained proportional to that of the latter, the proportionality however being variable by adjustment of resistance device 18 as in Fig. 2. Also said element 16^a is adapted to act merely mechanically for tripping latch 17^a subject to a definite predetermined time element for accurately timed stopping of motor M, the controller also being automatically reset. The abutment 19 serves to limit the degree of counterclockwise movement of latch 17^a, as noted in connection with latch 17, Fig. 2.

In each of the aforescribed constructions it is to be observed that the value of the heat energy applied to the thermo-responsive element is substantially independent of the power consumption of the motor but is maintained proportional to the energy consumption of the switch closing coil, which latter value is substantially a constant, whereby extreme accuracy and uniformity of the time element of response, subject to accurate calibration, is provided.

What I claim as new and desire to secure by Letters Patent is:

1. In a controller for electric motors and the like, the combination with control means for the motor and thermo-responsive timing inductive means for said control means, of means to subject said thermo-responsive means to thermic influence of a value substantially independent of the value of energy consumed by the controlled motor. 75

2. In a controller for electric motors and the like, the combination with electro-magnetically operable control means for the motor and thermo-responsive timing means for said control means, of inductive means to subject said thermo-responsive means to thermic influence of a value proportional to the value of energization of said electro-magnetically operable means but substantially independent of the value of energy consumed by said motor. 80

3. In a controller for electric motors and the like, the combination with electro-magnetically operable control means for the motor and thermo-responsive timing means for said control means, of means to be inductively energized by flux of said electro-magnetically operable control means for subjecting said thermo-responsive means to thermic influence of a value substantially independent of the 95 value of energy consumed by the motor.

4. In a controller for electric motors and the like, the combination with a switch and electro-magnetic operating means therefor comprising a field member having an energizing coil, of thermo-responsive means for controlling energization of said coil and means associated with said switch operating means to be inductively energized by flux traversing said field member for subjecting 100 said thermo-responsive means to thermic influence of a value substantially independent of the value of energy consumed by the motor. 105

5. In a controller for electric motors and the like, the combination with a switch and electro-magnetic operating means therefor comprising a field member having an energizing coil, of thermo-responsive means for shunting said coil, the latter having associated means to be traversed by inductively 110 created current for subjecting said thermo-responsive means to thermic influence. 115

6. In a controller for electric motors and the like, the combination with a switch and electro-magnetic operating means therefor comprising a field member having an energizing coil, a switch to control continuity of the circuit of said coil, means providing for definitely timed deenergization of said coil, comprising a thermo-responsive contactor 120 operable sequentially to shunt said coil and to cause opening of said switch, and inductive means to subject said thermo-responsive means to a definite value of thermic influence. 125

7. In a controller for electric motors and 130

the like, the combination with a switch and successive values of response of said grid electro-magnetic operating means therefor comprising a field member having an energizing coil, a latching-in switch to control the same is adapted to shunt said coil and thereafter to trip said switch for resetting the controller.

5 continuity of the circuit of said coil, a thermo-responsive grid to be energized by a value of current proportional to that traversing said coil and associated means whereby upon

In witness whereof, I have hereunto subscribed my name.

FREDERICK H. OBERSCHMIDT.

CERTIFICATE OF CORRECTION.

Patent No. 1,691,735.

Granted November 13, 1928, to

FREDERICK H. OBERSCHMIDT.

It is hereby certified that error appears in the printed specification of the above numbered patent requiring correction as follows: Page 2, line 71, claim 1, strike out the word "inductive" and insert the same after the word "of" in the same line; and that the said Letters Patent should be read with this correction therein that the same may conform to the record of the case in the Patent Office.

Signed and sealed this 8th day of January, A. D. 1929.

(Seal)

M. J. Moore,
Acting Commissioner of Patents.
